UNITED STATES PATENT OFFICE

NATHAN M. LOWER, ALBERT R. CHALKER, AND RALPH L. McCURDY, OF PITTSBURGH, PENNSYLVANIA, ASSIGNEES, BY MESNE ASSIGNMENTS, TO THE STANDARD STOKER COMPANY INC., OF NEW YORK, N. Y., A CORPORATION OF DELAWARE

LOCOMOTIVE STOKER

Application filed June 6, 1927. Serial No. 196,683.

The invention relates to locomotive stokers of the type in which the fuel is projected into the firebox by means of oscillating shovels or blades.

5 The objects of the invention are to provide a compact, rugged and highly efficient stoker to provide for the independent control of the means for transferring fuel from the locomotive tender, and means for elevating it to 10 a point of delivery and delivering it into the firebox.

The invention consists in a structure such as is hereinafter described and is illustrated in the accompanying drawings in which:

15 Fig. 1 is a detail central longitudinal vertical section of a locomotive and its tender with the improved stoker applied thereto some parts being omitted;

20 Fig. 2 is a detail plan view partly in section viewed from a plane passing through the firing door of the locomotive some parts being omitted;

25 Fig. 3 is a detail elevation of the rear end of the locomotive, showing in elevation the parts of the stoker mechanism which are mounted on the locomotive;

30 Fig. 4 is a central vertical longitudinal section of the elevating and distributing portion of the stoker and of the forward end of the conveyor;

Fig. 5 is a detail transverse vertical section on the line 5—5 of Fig. 4;

35 Fig. 6 is a transverse vertical section partly in elevation, of the driving mechanism for the fuel transferring means, and,

Fig. 7 is a detail sectional view on the line 40 7—7 of Fig. 6, portions of the stoker casing being shown in elevation.

In the firing of a locomotive it is essential that provision be made for varying the amount of fuel delivered to the firebox as the load imposed upon the locomotive is varied, as by changes in track grade and length and lading of the train.

45 In stokers of the type to which this invention relates it is important that the oscillating, feeding and distributing shovels or blades be normally driven at uniform speeds regardless of the amount of fuel being delivered, for the reason that they must scatter

the fuel evenly over the entire grate surface, which in stoker fired locomotives is of large area. In trimming the fire the shovels must make their impelling or forward stroke at velocities above or below the normal in order 55 to throw a larger percentage of the fuel to the front end of the firebox, or deliver it all in the rearward portion thereof, and to secure this regulation it is desirable that they be operated at higher or lower speeds. Regardless of the speed at which these fuel projectors are operated, the volume of fuel delivered per minute should be under complete control, either remaining uniform or being increased or decreased as the condition of the fire may 65 require; and to this end it is important that the rate of delivery into the zone of action of the distributors be capable of independent adjustment.

The improvements forming the subject of 70 this application provide for the desirable operations above pointed out.

In the drawings there is shown at 10 the usual hollow back head of a locomotive boiler; at 11 the grate of the firebox and at 12 75 the ordinary hand firing door opening which is provided with any suitable door, as 13. At 14 there is shown a part of the frame of the locomotive, and at 15 the forward end of the tender. The floor 16 of the fuel bin of the 80 tender is provided with a central longitudinal aperture within which are fitted, as shown, a number of slide plates, in accordance with common practice, for shifting the discharge opening for the fuel as the volume of the 85 fuel in the bin varies.

Immediately below this fuel bin opening there is located a conveyor trough 17, the forward end 18 of which takes the form of a tube. Movement of this trough incident to the relative movements of the locomotive and tender is provided for in part by mounting the trough upon a pair of rollers 19, 19 which rest upon track elements 20, 20 supported 90 from the frame of the tender and extending 95 longitudinally thereof.

Within the trough 17 and extending to the front end of its tubular portion is a conveyor screw 21, the rear end of which is suitably journalled in the back end of the trough, its 100

forward end preferably resting and turning upon the bottom of the trough as shown. The shaft of this screw projects through the rear end of the trough and carries a gear 22 which meshes with and is driven by a pinion 23 on a universally jointed and telescopically extensible drive shaft 24. A suitable fuel crusher, as 25, is mounted on the trough near the forward end on its open portion. The forward end 18 of the conveyor trough or conduit is connected by means of a ball and socket joint 26 with the casing 27 enclosing the stoker parts which are carried by the locomotive.

The forward end of the shaft 24 is universally jointed, as shown at 28, to the shaft 29 of a worm wheel 30, enclosed within a casing 31 attached to, or forming a part of the casing 27, and meshing with and being driven by a worm 32 formed on a shaft 33 which forms an extension of an engine shaft 34, to which it is coupled by means of the sleeve 35. The shaft 33 is carried by bearings 36, 37 mounted in the casing which encloses a worm wheel 30. These bearings are of the ball or roller type and take the thrust of the shaft in either direction. An element 38 of one of the bearings, as 37, is in threaded engagement with the walls of an aperture in the casing 31, to provide for the necessary bearing adjustment, and a lock 39 is provided for holding this element in adjusted position.

Any suitable motor may be employed for driving the conveyor screw. There is shown for this purpose at 40 a high speed four-cylinder reciprocating engine, of which the shaft 34 is the crank shaft, which carries a fly wheel 41.

Economy of space is conserved by locating the engine 40 on the locomotive, below the deck or floor of its cab and at one side of the casing 27, the engine shaft 33 extending through this casing and the worm wheel 30 and its casing being located upon the opposite side thereof.

A plunger elevator 42 reciprocates within the chamber of the casing 27, in ways which are inclined forwardly and upwardly. This elevator receives on its face a load of the fuel which has been delivered to the casing by the screw 21 and delivers it into a shovel box 43 mounted on the top of the casing 27, the front end of the box being open to the firing opening 12. A pair of oscillating shovels or vanes 44, 45 are mounted within the shovel box 43, being carried by vertical shafts located near the open end of the box. These shovels or vanes may be of any preferred form, being shown as of the type disclosed in Patent Number 1,304,464 to Elvin and Fahnestock. They are actuated alternately, swinging forwardly from the position of rest (as occupied by the shovel 44, Fig. 2), sweeping across an aperture 46 in

the bottom of the shovel box, through which the fuel is delivered by the elevator 42, and over an extension plate 47 leading forwardly from the bottom of the box through the fire opening 12 and preferably resting upon the bottom thereof.

The elevator 42 and the shovels 44, 45 are actuated by a suitable motor 48, there being shown for this purpose the well known Dake steam engine, the casing of which is suitably secured to the casing 27 and at the side thereof opposite to that at which the engine 40 is located. The crank shaft 49 of the engine 48 is coupled by means of a sleeve 50 to a worm shaft 51 located within the casing 27 and carrying a fly wheel 52. The engine shaft 49 projects through a sleeve 53 carried by the engine frame, a stuffing box 54 being applied to the end of this sleeve to prevent the escape of oil. A stuffing box 55 is also applied to the aperture through which the shaft 49 enters the casing 27 for the same purpose, it being the intention to partially fill with oil the portion of the casing 27 within which the operating mechanism is enclosed. The worm shaft 51 is journalled in brackets 56, 57 rising from the bottom of the casing 27, ball or roller bearings being employed which take the thrust of the shaft in either direction, and there being provided suitable means for the adjustment of these bearings, as indicated at 58.

It is sometimes necessary to turn the stoker mechanism by hand, as when relatively adjusting certain of the parts, or in making repairs, work that is usually done when the locomotive is not under steam, and to this end the fly wheel 52 is provided with gear teeth 59 for cooperation with a pinion 60 on a shaft 61, the end of which is square for the application of a hand crank. The shaft 61 is journalled in a casing 62 secured to the outer wall of the casing 27, and the outer end of the casing 61 takes the form of a stuffing box to prevent the escape of oil. As the use of the hand crank is only occasional, the pinion 60 is preferably normally out of engagement with the fly wheel, the shaft 61 being withdrawn by a spring 63 housed within the casing 62.

The worm on the shaft 51 drives a worm gear 64, which is fixed upon a sleeve 65 journalled upon a fixed shaft 66 secured in the front wall 61 of the casing 27, and in a partition 68 crossing the chamber of the casing 27 and separating it into two compartments, to one of which the fuel is delivered by the screw 21 and within the other the driving mechanism for the elevator and projectors is housed. This partition 68 also serves in part as the guide for the elevator 42.

Upon the end of the sleeve 65 opposite from that upon which the worm gear 64 is mounted, there is fixed a gear wheel 69 which meshes with a pinion 70 fixed upon a shaft 71

5 journalled in suitable boxes secured to the partition 68 and carrying a crank arm 72 which is connected by a pitman 73 to the elevator 42. In order to economize space the lower wall of the casing 27 is open below the elevator, as indicated at 74, to provide clearance for the crank arm 72. A second partition 75 extends upwardly from the bottom of the casing 27 approximately to the 10 level reached by the face of the elevator plunger 42 on its down stroke, and constitutes one of the ways within which the elevator travels. A skirt 76 depends from the elevator plunger 42 and engages the inner 15 face of the wall 75, the length of this skirt being such that it does not pass beyond the upper margin of the wall when the elevator is at the end of its up-stroke. The wall 75 and skirt 76 prevent the entry of fuel below 20 the elevator.

25 A cam wheel 77 is fixed upon the sleeve 65 intermediate of its ends and actuates the shovels 44, 45 through connections substantially as shown in Patent No. 1,267,644 to Elvin, Fahnestock and Clark, issued May 28, 1918, which need not be described in detail. There is mounted on the shaft of each of the shovels a pinion 78 with which meshes a segmental gear 79 carried by an oscillating 30 arm 80 having connection with the cam groove in the wheel 77.

35 Steam is led to the motor 40 through a pipe 81 and to the motor 48 by a pipe 82. Both of these pipes branch from the steam pipe 83 leading from the steam turret 84 of the locomotive. A hand valve 85 in the pipe 83 cuts off the steam from both motors. Each of the pipes 81, 82 is provided with a hand valve 86, 87, whereby the motors may be independently controlled. It being desirable that the 40 projecting shovels be not entirely stopped when the transfer conveyor is being operated, to the end that jamming may not occur, a small by-pass 88 leads around the valve 87 insuring some action of the motor 48 whenever the valve 85 is open.

45 The stoker organized as described is comparatively light, adding but little to the weight of the locomotive. It is compact and does not encroach upon the fuel bin of the tender or reduce its tank capacity. The transferring means, being driven by an independent motor, is capable of regulation independently of the elevating and distributing mechanism, and furthermore, does not disturb in the slightest degree the action of the latter if clogged or retarded, as by the sudden development of an excessive load by the necessity of crushing a lump of fuel.

50 The elevating and distributing mechanism, being actuated by an independent motor, may be regulated, as for the trimming of a fire, without affecting the action of the transfer mechanism, thereby providing for a uniform delivery of fuel to the firebox regardless

of the proportion of the grate upon which it is to be deposited.

The parts of the mechanism are easily assembled and are readily accessible for repair.

70 While a highly efficient and a preferred form of construction of the stoker as a whole, and its various parts has been disclosed, the invention in its broader aspects is capable of different forms of embodiment.

We claim as our invention:

75 1. A locomotive stoker comprising means for transferring fuel from a storage bin to the locomotive, and means for delivering the transferred fuel to the firebox of the locomotive, independent steam motors for driving the transferring means and the delivery means, a valve controlled steam pipe for both motors, valve controlled branches leading from such pipe to each motor, and a by-pass around the valve in one of the branches.

80 2. A locomotive stoker comprising means for transferring fuel from a storage bin to the locomotive, and means for delivering the transferred fuel to the firebox of the locomotive, independent steam motors for driving the transferring means and the delivery means, a valve controlled steam pipe for both motors, valve controlled branches leading from such pipe to each motor, and a by-pass around the valve in the branch leading to 85 the delivery means motor.

90 3. In a locomotive stoker, in combination, means for transferring fuel from a tender to a locomotive, means for delivering the transferred fuel to the locomotive firebox, a casing 100 inclosing the delivering means and receiving from the transferring means, separate motors for driving the transferring and the delivering means, such motors being located on opposite sides of the casing, a shaft actuated by each motor and projecting into the casing, and gearing within the casing and connected with each shaft and being in driving connection with the respective fuel moving means.

105 4. In a mechanical stoker, the combination 110 of a fuel bin, having delivery openings, a feed trough located below said openings, a screw conveyor and a fuel crusher within the trough, a delivery appliance receiving from said feed trough, a casing inclosing such appliance, and independent motors for operating the conveyor and the delivery appliance, such motors being attached to and supported by the casing.

115 5. In a locomotive stoker, in combination, 120 mechanical means for elevating fuel and delivering it to the firebox of a locomotive, a casing inclosing such means, and enclosing a worm gear, a motor located outside of the casing, a shaft within the casing connected with the motor shaft, a worm on the first-named shaft operatively engaging the worm gear, and hand actuated means for turning the worm shaft.

125 6. In a locomotive stoker, in combination, 130

mechanical means for elevating fuel and delivering it to the firebox of a locomotive, a casing inclosing such means, and enclosing a worm gear, a motor located outside of the casing, a shaft within the casing connected with the motor shaft, a worm on the first-named shaft operatively engaging the worm gear, a fly wheel on the worm shaft having gear teeth, a spring retracted longitudinally movable crank shaft journaled in the casing wall, and a pinion on the crank shaft adapted to engage the gear teeth of the fly wheel.

7. In a locomotive stoker, in combination, means for transferring fuel from the locomotive tender, a casing on the locomotive receiving the transferred fuel, means within the casing for delivering the fuel therefrom to the firebox of the locomotive, a motor at one side of the casing and having a crank shaft projecting thereinto, a worm on the shaft, a worm wheel within the casing driven by the worm, and a shaft driven by the worm wheel for actuating the transferring means.

In testimony whereof we affix our signatures.

NATHAN M. LOWER.
